PRODUCTION OF MOTOR FUEL

Herbert H. Meier, Baytown, Tex., assignor to
 Standard Oil Development Company, a corpora-
 tion of Delaware

Application April 13, 1939, Serial No. 267,580

10 Claims. (Cl. 196—10)

The present invention is directed to the production of hydrocarbon motor fuels, and, particularly, to those fuels which are known as aviation gasolines because they satisfy certain vapor pressure and octane number requirements.

In the cracking of crude oils and distillates thereof, there are produced large amounts of lower boiling hydrocarbons, such as C₄ and C₅ hydrocarbons. Some of the members of these groups are highly desirable constituents of motor fuels, particularly aviation gasoline because of their high octane number blending value and their vapor pressures. On the other hand, these fractions contain a number of constituents which are undesirable because of their detrimental effect on the octane number of gasoline.

More specifically, isopentane and the various amylanes are desirable constituents in a finished gasoline, while normal pentane is an undesirable constituent. Because of the presence of the various amylanes in the mixture, separation of the isopentane from the normal pentane is impractical from an economic standpoint. Moreover, normal pentane cannot be removed from the mixture without removing certain amylanes the presence of which is desirable.

According to the present invention, the isopentane in such cracked products is made available and the normal pentane is made readily separable without sacrificing any of the amylanes by isolating the C₅ fraction and alkylating it with isobutane or, if desired, with higher isoparaffins. Isobutane is preferred for this purpose because it reacts with the amylanes in the presence of a suitable alkylation catalyst, such as sulfuric acid, aluminum chloride, BF₃, and the like, to produce a product which is rich in iso-octanes. This product usually contains the same or a greater amount of isopentane than the amount contained in the original C₅ cut.

According to the present invention, the product obtained from the alkylation of the C₅ fraction is readily fractionated into a C₄ fraction which will be composed substantially entirely of excess isobutane, which can be recycled to the alkylation unit, an isopentane fraction, which can be reblended with the original base stock, if the latter is suitable for aviation gasoline, or with a base stock selected for this purpose, a normal pentane fraction, which can be utilized in motor gasoline for fill, and a fraction ranging from C₆ hydrocarbons upwardly, which itself may be used as a base stock for aviation gasoline or can be blended with the same base stock to which the isopentane fraction is added. A separation

of the isopentane from the normal pentane is simplified by the method of the present invention by reason of the elimination of the amylanes which, in turn, are converted into highly desirable constituents for aviation gasoline.

In a specific embodiment of the present invention, cyclopentane is isolated for use as a blending agent for octane number improvement. Cyclopentane, by reason of its boiling point, is readily separable from the various hexanes, except 10 2-2-di-methylbutane which of itself, however, is an isoparaffin of high octane number blending value and, therefore, a desirable adulterant for the cyclopentane. In the practice of this embodiment, the initial C₆ cut is cut high enough to include cyclopentane which is fed through the alkylation zone with the C₅ cut and the added isoparaffin, and is then recovered from the product after the recovery of normal pentane. In other words, the practice of this specific embodiment includes an additional fractionating step on the alkylation product.

The present invention will be better understood from a detailed description of the accompanying drawing in which the single figure is a front elevation in diagrammatical form of a plant suitable for its practice.

Referring to the drawing in detail, numeral 1 designates a fractionating tower to which is fed 30 through line 2 a cracked distillate or any other mixture of hydrocarbons containing C₆ and lighter olefins and isoparaffins. The tower is preferably so operated as to produce an overhead containing C₃ and lighter hydrocarbons, a side stream containing C₄ hydrocarbons, a second side stream containing C₅ hydrocarbons, and bottoms containing C₆ and heavier hydrocarbons. The overhead leaves the tower through line 3, the C₄ fraction leaves the tower through line 4, the C₅ fraction leaves the tower through line 5, and the bottoms leave the tower through line 6.

The mixture recovered through line 5 is fed to an alkylation zone 7 which, for expediency, is represented by a simple rectangle, but which will be understood to be a conventional alkylation unit in which is circulated a mixture of alkylation catalyst, such as sulfuric acid of a strength preferably in excess of 90%, alkylation product, and unreacted initial material, and from which 45 is continuously withdrawn a certain portion which is separated into alkylation product, alkylation catalyst and unreacted initial material, the first being fed to a suitable refining and fractionating apparatus, and the second and third 50 being returned to the circulating stream. To

this alkylation zone through line 8 is also fed isobutane or other selected isoparaffin.

The alkylation product is introduced into a debutanizing tower 9 which is maintained under pressure and temperature conditions such that unreacted isobutane is discharged from the top through line 10 and recycled to feed line 8, and stabilized product is discharged from the bottom through line 11 into a fractionating tower 12, which is maintained under suitable pressure and proper temperature to yield an overhead composed essentially of isopentane which leaves the tower through line 3.

The isopentane-free product is withdrawn from the bottom through line 14 and discharged to a second fractionating tower 15, which is so controlled as to yield an overhead composed mainly of normal pentane which leaves the tower through line 16. With particularly good fractionating equipment, tower 15 may be dispensed with and the normal pentane recovered from tower 12 as a side stream.

The pentane-free product leaves tower 15 through line 17 and is discharged into a further fractionating tower 18 which is so operated as to produce a C₈ and lower fraction and a C₉ and heavier fraction, the latter leaving the tower at the bottom through line 19 and the former leaving the top of the tower through line 20. Depending on the character of the aviation gasoline desired and the blending requirements, the overhead from tower 18 may be varied so as to include some of the C₉ hydrocarbons.

As previously indicated, isopentane recovered from the system through line 13 and the C₈-fraction recovered from the system through line 20 may, in some instances, be blended together to produce an aviation gasoline, or may both be blended with a suitable straight run base stock for this purpose. Also as previously indicated, when the initial C₅ cut is so selected as to contain cyclopentane, this hydrocarbon may be recovered as a side stream from tower 15 or as an overhead from a tower interposed between tower 15 and 18. It may be mentioned here also that in the initial fractionating tower 1 it is not necessary to recover a C₄ fraction and a C₅ fraction independently, because most of the advantages of the present method can be secured by blending these fractions or recovering them in a single stream and feeding them to the alkylation unit.

The conditions to be employed in the alkylation zone are well known, but may be recapitulated briefly as follows:

The temperature selected may be any temperature below about 150° F. and is preferably room temperature or lower, excellent results having been obtained at temperatures between about 20 and 70° F. and particularly at about 35° F. The operating pressure is made sufficiently high to maintain the reactants in the liquid state at the temperature employed. Generally, a large excess of added isoparaffin to olefin will be maintained in the reaction mixture by maintaining a high ratio of recycle stock to feed stock and by maintaining a ratio at least 2:1 and preferably at the order of 10:1 of added isoparaffin to olefin in the feed stock. As is known, fresh make-up acid should be substituted periodically for a corresponding portion of the reaction acid so as to maintain acid strength at the desired level.

It will be understood that the present invention is not limited to the employment of any particular catalyst in the alkylation zone or to the maintenance of any particular operating con-

ditions in that zone or to any particular source of C₅ hydrocarbons. What the invention is primarily concerned with is rendering available isopentane from a mixture of hydrocarbons containing it in combination with normal pentane and amylanes with the simultaneous conversion of the amylanes into desirable aviation gasoline constituents.

The nature and objects of the present invention having thus been described and illustrated, what is new and useful and is desired to be secured by Letters Patent is:

1. A method for recovering isopentane from a hydrocarbon mixture containing it in combination with normal pentane and amylanes which comprises reacting the mixture with an added isoparaffin other than isopentane in the presence of an alkylation catalyst, and recovering a fraction essentially composed of isopentane from the alkylation product.

2. A method for recovering isopentane from a hydrocarbon mixture containing it in combination with normal pentane and amylanes which comprises reacting the mixture with an added isoparaffin other than isopentane in the presence of sulfuric acid of a strength in excess of about 90% at a temperature and for a time suitable for the alkylation of the added isoparaffin by the amylanes, and recovering from the product of this alkylation a fraction essentially composed of isopentane.

3. A method according to claim 1 in which the added isoparaffin is isobutane.

4. A method according to claim 2 in which the added isoparaffin is isobutane.

5. A method for producing blending agents of high octane number from a hydrocarbon mixture containing isopentane, cyclopentane, normal pentane and amylanes which comprises reacting the mixture with added isobutane in the presence of an alkylation catalyst, and recovering from the alkylation product a fraction essentially composed of isopentane and a fraction essentially composed of cyclopentane.

6. A method for producing blending agents of high octane number from a hydrocarbon mixture containing isopentane, cyclopentane, normal pentane and amylanes which comprises reacting the mixture with added isobutane in the presence of concentrated sulfuric acid of a strength in excess of about 90% at a temperature and for a time suitable for the alkylation of the added isoparaffin by the amylanes, and recovering from the alkylation product so produced a fraction essentially composed of isopentane and a fraction essentially composed of cyclopentane.

7. A method for producing aviation gasoline which comprises reacting a mixture containing isopentane, normal pentane and amylanes with added isobutane in the presence of an alkylation catalyst to produce an alkylation product, separating from the alkylation product a fraction essentially composed of isopentane, a fraction essentially composed of normal pentane, and a fraction containing a large percentage of C₈ hydrocarbons, and combining the first and third fractions.

8. A method for producing aviation gasoline which comprises reacting a mixture containing isopentane, normal pentane and amylanes with an excess of added isobutane in the presence of sulfuric acid of a strength exceeding about 90% at a temperature and for a time suitable for the alkylation of the added isoparaffin by the amylanes, recovering from the alkylation product so

produced a fraction essentially composed of isopentane, a fraction essentially composed of normal pentane, and a fraction containing a large percentage of C₈ hydrocarbons, and combining the first and third fractions.

9. A method of segregating isopentane from a C₅ fraction containing paraffins and olefins while producing a high octane number, saturated, branched chain hydrocarbon fraction containing substantial amounts of C₈ constituents which 10 comprises reacting and alkylating a C₅ hydro-

carbon fraction containing isopentane, normal pentane and amylenes with added isobutane under alkylating conditions in the presence of an alkylation catalyst, fractionating a C₅ paraffinic fraction from the reacted mixture and separating isopentane therefrom.

10. A process as in claim 9 wherein unreacted isobutane is recovered from the reaction product and returned to the alkylation reaction, and wherein a C₆—C₈ alkylate is recovered.
